(57) **CLAIM**

The ornamental design for a golf club head, as shown and described.

DESCRIPTION

FIG. 1 is a top rear perspective view of a golf club head showing our new design;

FIG. 2 is a top view thereof;

FIG. 3 is a rear view thereof;

FIG. 4 is a heel end view thereof; and,

FIG. 5 is a toe end view thereof.

The difference in shading between the two shaded regions indicates a contrast of appearance and does not depict any particular color, texture, or material. The broken line immediately adjacent to the shaded region forms an unclaimed boundary of the design. The broken line showing of the remainder of the golf club head is for illustrative purposes only and forms no part of the claimed design.
